PACKAGE-MAKING MACHINE

Alfred German Rose, Gainsborough, England, assignor to Rose Brothers (Gainsborough) Limited, Gainsborough, England, a British company

Application August 16, 1934, Serial No. 740,108
In Great Britain June 15, 1933

9 Claims. (Cl. 93—2)

This invention relates to package-making machines of the kind wherein each article of a succession of articles is fed by means of a pusher along a rectilinear path, a wrapper (of paper or 5 similar material) is fed into the path of travel of said article and pusher, adhesive is applied to portions of the wrapper, folding means cooperate with the forward travelling movements of the article and wrapper to fold the wrapper about the article into an open-ended pouch, and other folding means fold rearwardly-projecting flaps of the pouch in so as to enclose the article 10 completely within the wrapper and form a package.

15 The object of the present invention is to provide an improved machine of this kind incorporating certain novel features of construction and operation in order to render the machine more simple and more reliable and efficient in 20 operation at a higher speed than prior machines of this kind.

According to the present invention a package-making machine comprises in combination a horizontal rectilinear channel-shaped runway, 25 means for feeding a wrapper in a plane transverse to the length of the runway into a position in which it is adjacent one end of the runway and substantially symmetrical with respect thereto, a device for applying adhesive to the paper, means for feeding an article into alignment with the runway and to the side of the wrapper remote from the runway, a pusher, 30 means for moving the pusher, with the article and wrapper, along the runway, and folding devices provided in the runway to fold the wrapper into an open-ended pouch about the article.

According to a feature of the present invention, the adhesive-applying device comprises a pair of sectors mounted to rotate about an axis, 40 which is preferably horizontal, parallel to the plane of the wrapper and transverse to the direction, which is preferably vertical, in which the wrapper is fed to engage the wrapper on their peripheries and apply adhesive to it as it is fed into position and means for supplying adhesive to the peripheries of the sectors. Preferably the sectors are driven and there are provided rollers mounted opposite them on the other side of the plane of the wrapper to co-operate with them in feeding the wrapper into position.

According to another feature of the present invention there is provided a corrugating device through which each wrapper is fed on its way to the position in alignment with the runway and which is arranged to produce shallow, wave-like

corrugations in the wrapper, so as to impart a certain degree of stiffness to the wrapper and enable it to support itself in position opposite the runway.

Preferably the corrugating device comprises two rows of corrugating elements which rows are arranged one on each side of, and parallel to, the plane in which the wrappers move and extend transversely to the direction of movement of the wrapper and each of which elements extends across said plane from its side thereof and is opposite a gap between the elements of the other row. With this arrangement as a wrapper is fed between the two rows of elements portions of it are pressed by the elements out of its general plane so as to produce shallow, wave-like corrugations in it. Means may be provided for feeding a continuous web of wrapping material through the corrugating device and severing means may be provided for severing the portion 20 of the wrapper material that has passed the corrugating device from the web, to form a wrapper. Owing to the corrugations in it the severed web is more or less self-supporting.

According to yet a further feature of this invention, an adhesive-applying device may be provided for applying adhesive to one surface of a rearwardly-projecting flap of the wrapper as the latter is fed along the runway.

The present invention also includes a machine 30 which is provided with a vertical transfer channel, a supporting device normally located near the lower end of the transfer channel in position to receive an article and its wrapper delivered along the runway and to raise the article when completely wrapped into the transfer channel and 35 means for folding rearwardly-projecting flaps of the wrapper in while the article is supported on the supporting member.

A preferred embodiment according to the present invention will now be described by way of example only with reference to the accompanying drawings, in which:

Figures 1 and 1a together form a side elevation of a package-making machine according to this 45 invention, with one side frame removed.

Figure 2 is a section along the line 2—2 of Figures 1 and 1a.

Figure 3 is a section along the line 3—3 of Figures 1, and

Figures 4, 5, 6, 7 and 8 show various stages in the formation of a single package by the machine.

Like reference characters indicate like parts in all the figures of the drawings.

The machine comprises a main cam-shaft 10 55

(Figure 1) on which a gear-wheel 11 is secured. This gear-wheel meshes with a gear-wheel 12 secured on a shaft 13. A crank 14 is secured on this shaft and is connected by a link 15 to a lever 16 (Figure 1a), the upper end of which is pivoted on to a block 17. The block 17 moves in horizontal guides 18. At its lower end the lever 16 is pivoted on a link 19 which, in turn, is pivoted on a fixed stud 20. As the shaft 10 rotates, the block 17 is reciprocated horizontally along the guides 18. The block 17 carries a pusher 21.

Referring to Figure 2, a succession of articles A are fed one at a time along a track 23 by a plunger 22 into the path of movement of the pusher 21.

A continuous web of wrapping material 24 (Figure 1) is fed downwardly by feed rollers 25 which are driven in any suitable manner. After leaving the feed rollers the web 24 passes through a corrugating device which is shown in Figures 1 and 3. This device comprises a guide chute having a front plate 26 and a rear plate 27 which are secured together by screws and are supported by rods 28 on suitable pillars 29. As shown in Figure 3, the guide plate 26 is formed with two ridges 30 and the guide plate 27 with three ridges 31. As indicated in Figure 1, the ridges 30 are opposite the gaps between the ridges 31 and vice versa. The free edge of each ridge extends across the general plane of the wrapper so that, as seen in Figure 1, the edges of the ridges overlap. As the wrapper passes through this device, shallow, wave-like corrugations will be given to it so as to impart a certain amount of longitudinal stiffness to it.

After the wrapper web leaves the corrugating device it passes through a second guide chute 32 which also comprises two plates secured together and supported by the pillars 29. As can be seen from Figure 2, this guide chute is provided with a series of ridges 33 which serve to guide the paper without, however, smoothing out the corrugations which have been imparted to it.

After a sufficient length of web has passed the corrugating device to form a single wrapper, a knife 34 is operated in any suitable manner to sever the wrapper and the severed portion moves downward until arrested by a stop 35. The severed portion or wrapper W is then in the position shown in Figures 1 and 4. As the wrapper W moves down to this position, gum or other adhesive is applied to it at the position marked G in Figure 4. The mechanism by which the adhesive is applied will now be described.

The shaft 13 carries a sprocket-wheel 36 which by a chain 37 drives a shaft 38. This shaft 38 carries a gear-wheel 39 which meshes with a gear-wheel 40. The gear-wheel 40 meshes with a gear-wheel 41 which is secured on a shaft 42. This shaft carries a pair of sectors 43 which engage the outer surface of a wrapper W as the latter moves downward and apply the gum to it. The sectors 43 press the wrapper against rollers 44 which are carried on a shaft 45. This shaft carries a gear-wheel 46 which meshes with the gear-wheel 41 so that the sectors 43 and rollers 44 rotate in synchronism and serve to feed the wrapper W downwards against the stop 35 after it has been severed from the web.

The gear-wheel 40 is secured to a gum-roller 47 which picks up gum from a trough 48 and applies it to the peripheries of the sectors 43.

After the wrapper and article have been positioned, as shown in Figures 1, 2 and 4, the pusher 21 moves to the left so as to force the article

against the wrapper and to feed both the article and the wrapper into a rectilinear runway 49. The upper and lower portions of the wrapper are folded against the top and bottom surfaces of the article by the upper and lower lips 50 and 51 of the runway and at the same time the vertical flaps of the wrapper projecting from each side of the leading surface of the article are folded inwardly by folding members 52 (Figure 1). Thus, as the article and wrapper enter the runway, the wrapper is folded about the article as shown in Figure 5.

As the incomplete package moves further into the runway, the laterally-projecting portions 54 (Figure 5) of the lower part of the wrapper are folded upwards against the article by edges 53 of the side walls of the runway. This brings the gummed surface to the outside of the package and against the sides of the article. As the incomplete package moves further along the runway the upper laterally-projecting flaps 55 (Figure 5) are folded downwardly by edges 56 (Figure 1) of the runway so as to overlie the previously folded flaps 54. The gum on the flaps 54 serves to retain the flaps 55 in position. The package is now in the state shown in Figure 6 and comprises an article enclosed in a pouch which is open at its rear end.

The shaft 38 carries three gum-applying arms 57 (Figures 1 and 2) which rotate constantly and pick up gum from the gumming-roller 47. These arms reach through a suitable opening in the floor of the runway 49 and apply gum to the lower surface of the lower rearwardly-extending flap of the package which at this time is in the condition shown in Figure 6. This flap thus receives three spots of gum.

The article is fed completely through the runway 49 and is delivered on to a supporting member 58 and into the lower end of a vertical transfer channel 59.

The next operation is to fold in rearwardly-extending side flaps 60 (Figure 6). This is effected by a pair of folding elements 61 which are formed on the ends of folding arms 62 and 63. These arms are pivoted on spindles 64 and 65 and are formed with inter-gearied sectors 66 so that they will rock together towards or away from one another. The arm 62 is secured to the spindle 64, the lower end of which carries an arm 67 which is pressed by a suitable spring against a cam 68 secured on the shaft 10. After the package has been moved on to the supporting member 58, the cam 68 causes the arms 62 and 63 to rock together so that the folding elements 61 engage and tuck in the flaps 60 as shown in Figure 7.

A lower projecting flap 69 (Figure 7) is next folded in by a folding member 70 (Figure 1) which is provided on the upper end of a link 71. This link is supported at its upper end by a link 72 and at its lower end by a lever 73 which is pivoted on a shaft 74. The lever 73 is rigid with a lever 75 which is pressed by a suitable spring (not shown) against a cam 76 on the shaft 10. After the side flaps 60 (Figure 6) have been folded in by the member 61 (Figure 2) the cam 76 causes the levers 75 and 73 to rock and raise the link 71 and folding element 70 so that this element engages and folds in the lower projecting flap 69 (Figure 7).

It will be seen from Figure 1 that the cam 16 is so shaped that the folding element 19 will pause in its upper position. While this element is pausing, a cam 77 causes a lever 78 to rock about the shaft 74. This lever is secured to a lever 79 on

which the supporting member 58 is carried. The member 58 is supported for parallel movement by the lever 79 and a link 80. Thus, while the folding element 70 is still raised, the package will be 5 raised by the member 58 upwardly in the transfer channel 59. During this movement an upper projecting flap 82 (Figure 7) will be engaged and folded inwardly by the lower edge 81 of one wall of the transfer channel 59. This flap 82 will be 10 held in position by the gum which was applied by the members 57 to the lower, and now outer, surface of the flap 69.

It is necessary to support the package in the transfer channel 59 while the pusher 21, which 15 has now moved back to the position of Figure 1, feeds a new incomplete package on to the supporting member 58 which will now be lowered. This is done by two ledges 83 (Figure 2) which are carried by arms 84 and 85. These arms are 20 mounted on spindles 86 and 87 and are interconnected by gear-sectors 88 so as to rock towards or away from one another. The spindle 87 carries a lever 89 which engages a cam 90. Immediately before the supporting member 58 commences to rise, the arms 84 and 85 are rocked apart so as to move the ledges 83 clear of the 25 throughway in the transfer channel 59 and allow of the package being raised. As soon as the member 58 reaches its uppermost position, the arms 84 and 85 are rocked together by the cam 90 so as to bring the ledges 83 into the throughway 30 of the transfer channel and immediately below the newly-completed package which is thus supported when the supporting member 58 again moves downwards. From Figure 2 it will be observed that the supporting member 58 is cut away at 91 on each side in order that the ledges 83 may be moved under the newly-completed package. The ledges move into the cut-away portions 91.

40 The term "adhesive" is used herein to include water or a solvent. Water may be used when the wrapper is already provided with a dry coating of gum and a solvent may be used when the wrapper is made of or coated with a material such as a cellulose derivative which will adhere to itself when moistened with the solvent. For pyroxylin a mixture of alcohol and ether may be used for moistening the wrapper, while for cellulose acetate a suitable moistening agent is aniline or pure acetic acid. These are given merely by way of example, as suitable solvents will be known to those skilled in the art for use with other materials used for the wrapper.

I claim:

55 1. A package-making machine comprising a horizontal runway, means for feeding an article along the runway, a pair of corrugating members located above the runway and comprising oppositely projecting overlapping portions, means for feeding a web of wrapping material downwardly 60 between the corrugating members in a plane transverse to the length of the runway, a knife arranged to sever the web below the corrugating members to form a wrapper, a stop located below the runway to arrest downward movement of the severed wrapper when it is in the path of the article along the runway, a pair of sectors mounted below the runway to turn about a horizontal axis to engage one surface of the wrapper, a co-operating pair of rollers to engage the other surface of the wrapper, means for rotating the sectors and rollers to feed a wrapper against the stop, means for supplying adhesive to the sectors, and folding elements adjacent the runway for folding the wrapper about the article.

2. A package-making machine comprising means for folding a wrapper into an open-ended pouch about an article, a support having a cut away portion at each side, means for feeding the article, enclosed in the wrapper, on to the support, a pair of end-folding members mounted to move towards one another across the unenclosed face of the article, means for moving said members together after the article is positioned on the support and then to separate them, a third 10 end-folding member mounted to reciprocate across the said unenclosed end of the article, means for moving the third end-folding member across said face, after the first two end-folding members have been separated, a vertical transfer-channel located above the support, means for raising the support to transfer the wrapped article into the transfer-channel and then lowering the support, a supporting ledge at each side of said transfer channel movable from the cut 20 away portions in the support and from the supporting position within the transfer channel below the raised position of the support to an inoperative position outside the transfer-channel and actuating means for the supporting ledge 25 operating in timed relation to the raising and lowering of the support for moving the ledge from its supporting position to its inoperative position before the support is raised and to restore it to its supporting position while the support is still raised.

3. A package-making machine comprising means for folding a wrapper into an open-ended pouch about an article, a support, means for feeding the article, enclosed in the wrapper, on to the support, a pair of end-folding members mounted to move towards one another across the unenclosed face of the article, means for moving said members together, after the article is positioned on the support, and then to separate them, 40 a third end-folding member mounted to reciprocate across the said unenclosed end of the article, means for moving the third end-folding member across said face, after the first two end-folding members have been separated, a vertical 45 transfer-channel located above the support, means for raising the support to transfer the wrapped article into the transfer-channel and then lowering the support, a pair of supporting ledges on opposite sides of the transfer channel, 50 means for simultaneously removing the ledges from a normal position within the transfer-channel at the uppermost level of the support before the support is raised and for simultaneously moving the ledges toward each other into normal 55 position while the support is in its uppermost position, the top of the support being cut away to permit the ledges to nest therewith beneath an article on the support.

4. A package-making machine comprising a horizontal runway, means for feeding a wrapper in a plane transverse to the length of the runway into a position in which it is adjacent one end of the runway, a device for applying adhesive to 60 the wrapper, means for feeding an article into and along the runway, folding devices provided in the runway to fold the wrapper into an open-ended pouch about the article, a pair of adhesive-applying arms mounted to rotate about a horizontal axis below the runway in position to engage the wrapper as it passes along the runway, means for so rotating the arms in synchronism with the passage of an article along the runway that they engage the rear portion of the lower 70 75

surface of the wrapper, and means for supplying adhesive to the arms.

5. A package-making machine comprising a horizontal runway, means for feeding an article into and along said runway, means for feeding a wrapper in a vertical plane transverse to the length of the runway in a vertical direction into operative position in the path of the article entering the runway, a stop for positioning the wrapper in said operative position, rotatable adhesive-applying means mounted adjacent the wrapper to engage the same when adjacent said operative position and feed the same against said stop, and folding devices adjacent the runway to fold the wrapper about the article as it passes along the runway.

6. A package-making machine comprising a runway, means for feeding an article into and along said runway, means for feeding a wrapper transversely to the length of the runway into operative position in the path of the article entering the runway, a stop for positioning the wrapper in operative position, a pair of adhesive-applying sectors rotatably mounted adjacent the path of the wrapper so as to contact with the wrapper and feed the same against said stop, means for rotating the sectors, means for supplying adhesive to their peripheries, and folding devices adjacent the runway for folding the wrapper about the articles as they pass along the runway.

7. A package-making machine comprising a horizontal runway, means for feeding an article into and along said runway, means for feeding a wrapper in a vertical plane transverse to the runway and in a vertical direction into operative position in the path of the article along the runway, a stop for positioning the wrapper in said operative position, a rotatable adhesive-applying device mounted to turn about a horizontal axis on one side of the path of the wrapper, wrapper-engaging means rotatably mounted on a parallel axis on the other side of said path in position to

cooperate with said rotatable device in feeding the wrapper into said operative position, means for rotating said adhesive-applying device, and folding devices adjacent the runway for folding the wrapper about the articles as they pass along the runway.

8. A package-making machine comprising a runway, means for feeding an article into and along said runway, means for feeding a wrapper transversely to the length of the runway into operative position in the path of the article entering the runway, a pair of adhesive-applying sectors rotatably mounted on one side of the path of the wrapper, wrapper-engaging means rotatably mounted on a parallel axis on the other side of said path in position to cooperate with the sectors in feeding the wrapper into operative position, a stop for positioning the wrapper in operative position, means for rotating said sectors so as to pass out of engagement with the wrapper immediately subsequent to the positioning of the wrapper against said stop, and folding devices adjacent the runway for folding the wrapper about the article as it passes along the runway.

9. A package-making machine comprising a runway, means for feeding an article into and along said runway, means for feeding a wrapper transversely to the length of the runway into operative position in the path of the article entering the runway, a device for applying adhesive to the wrapper, folding devices provided in the runway to fold the wrapper into an open-ended pouch about the article, a rotary adhesive-applying device beneath the path of travel along the runway and operable to apply adhesive to a rearwardly projecting flap of the wrapper in passing along the runway, and additional folding means for folding the rearwardly-extending flaps of the pouch folding first the flap to which the adhesive has been applied.

ALFRED GERMAN ROSE.
